UNITED STATES PATENT OFFICE.

JOHN J. HALLIWELL, OF MOUNT VERNON, NEW YORK, ASSIGNOR TO R. HOE AND CO.,
OF NEW YORK, N. Y., A CORPORATION OF NEW YORK.

FOLDING CYLINDER.

Application filed March 28, 1923. Serial No. 628,191.

To all whom it may concern:

Be it known that I, JOHN J. HALLIWELL, a citizen of the United States, residing at Mount Vernon, county of Westchester, and

5 State of New York, have invented certain new and useful Improvements in Folding Cylinders, fully described and represented in the following specification and the accompanying drawings, forming a part of 10 the same.

This invention relates to certain improvements in folding cylinders for high speed printing machines.

15 The rotary folders used in conjunction with high speed printing machines usually include a cylinder provided with a tucking blade which tucks off the sheet into the bite of a pair of co-operating folding rolls. This class of folding cylinder is provided with 20 suitable sheet taking devices, such as pins, which take the leading end of the web and carry it partially around the cylinder, a co-acting cutting mechanism being employed for cutting off the sheet.

25 After the sheet has been carried to a given point the sheet is released from the pins and the tucking blade tucks off the sheet into the folding rolls. The sheet has been released from the pins before it is tucked 30 off to prevent tearing of the sheet. It frequently happens that after the sheet has been released by the pins and before it has been tucked into the bite of the folding rolls, a slip of the sheet on the cylinder takes 35 place, this slip varying with the speed at which the cylinder is rotating so that the fold does not always come at the right point in the sheet. Furthermore, it is desirable to employ these folding cylinders in folding 40 off products of a different number of plies.

It is the especial object of the present invention to provide an improved folding cylinder construction whereby the sheet is held on the cylinder against a slip during a 45 time it is released from the pins and before it is tucked into the bite of the folding rolls, and which mechanism shall function to properly take care of a product having a varying number of plies, the construction 50 being such that the holding means will automatically adjust themselves to different thicknesses of products passing therebetween.

It is a further object of the invention to 55 provide a simple and efficient construction

for effecting this and one which can be readily associated with folding mechanisms already constructed as well as with new structures.

With these and other objects not specifically referred to in view, the invention consists in certain novel parts, arrangements and combinations, which will be fully described in connection with the accompanying drawings, and the novel features there- 60 after pointed out in the claims hereunto annexed.

In these drawings—

Figure 1 is a front view of so much of a rotary folding mechanism and its associated 70 parts as is sufficient for an understanding of the invention, part of the framing being broken away and certain of the shafts being shown in section.

Figure 2 is a side view of the improved 75 folding cylinder and certain co-operating parts.

Figures 3 to 6 inclusive are sectional views of the folding cylinder, certain of the parts being broken away showing the mechanism in different positions; Figure 3 showing the product released from the pins and tucked into the bite of the folding rolls; Figure 4 shows the sheet held by the pins before the folding blade comes into action; Figure 5 shows the parts in the position taken as the folding blade starts to fold off the sheet; and Figure 6 shows the sheet just before it enters the bite of the folding 80 rolls.

Figure 7 is a detail plan view of one of the spring seats.

Figure 8 is a detail sectional view thereof.

Referring now to these drawings, the parts of the mechanism are supported in framing 95 1 of any usual or suitable construction. The web W is led from a printing machine not shown, between the usual feeding rolls 2, 3 which act to feed the web forward, these rolls determining the length of the sheet to 100 be hereafter severed from the web, as is usual. If desired a second web W' may be associated with the web W, this web passing over a suitable guide roll 4. The web or webs then pass to the rotary folding mechanism which, in the particular construction illustrated, comprises a rotary folding cylinder 5 mounted on a shaft 6 suitably journaled in the machine frames. Co-operating 105 with this rotary folder 6 is, in the construc- 110

tion shown, a cutting cylinder 7 suitably mounted on a shaft 8, this cutting cylinder being provided with a cutting knife 9 which co-operates with the usual cutting woods 10 on the cylinder 5. In the particular construction illustrated, the cutting cylinder 7 may also act as a collecting cylinder where a collected product is desired, the cylinder 7 being provided with sheet taking devices, 10 as pins 11, these pins being operated in any usual or suitable manner.

The rotary folding cylinder 5 is provided with a rotary tucking blade 12 carried on a shaft 13, this shaft being operated in any 15 usual or suitable manner to be projected beyond the surface of the cylinder to fold off the sheet. The folding cylinder 5 is, also, provided with sheet taking devices, these sheet taking devices being arranged 20 in sets. The particular sheet taking devices shown are pins 14, these pins being carried on arms 15 mounted on shafts 16, these shafts being rocked to project the pins into the sheet path and to withdraw 25 them therefrom in the usual manner, as by cam rolls 17 co-operating with a cam 18 shown in Fig. 2.

In accordance with the invention means are provided for holding the sheet against 30 the cylinder so as to prevent any slip of the sheet between the time it is released from the pins and before it is tucked into the bite of the folding rolls, so that no matter what the speed of the cylinder the sheet always retains its correct position 35 thereon, and the fold in the sheet will always come on the same predetermined line. While the specific construction of these means may vary, the construction will be 40 such that they will yield so as to automatically adjust themselves to products of varying number of plies, and the construction will be such, furthermore, that while they will readily yield to accommodate such dif- 45 ferent products, the products will be securely held. A preferred form of device for this purpose is as shown in the drawings and as illustrated there is provided at each 50 end of the cylinder and just behind and closely adjacent to the pins yielding blocks 19, 20, these blocks having sheet engaging 55 faces 21. The sheet engaging faces of these blocks are sufficiently long to engage the sheet the required time to hold it against a slip after it has been released from the 60 pins and before it is tucked into the rolls, and these blocks are mounted so as to yield to accommodate products of varying number of plies within the capacity of the 65 folder. As shown, the blocks (see particularly Figs. 7 and 8) seat in recesses 22 in the cylinder wall against springs 23, these springs seating in recesses 24 and bearing against the under surface of the 70 blocks. The blocks are held in the recesses

22 in any suitable manner and, as shown, the blocks are provided at each end with reduced ends 25 which take under shoulders 26 formed in the cylinder wall.

Co-operating with the yielding blocks is 70 an abutment between which and the blocks the sheet passes, this abutment being arranged so that when the sheet is folded off by the folding blade and is nipped by the folding rolls the sheet will be freed from 75 the pressure between the blocks and the abutment whereby it may be freely pulled away by the rolls. In the particular construction illustrated, there is provided an abutment in the form of a plurality of 80 rolls 27 carried on a shaft 28 suitably journaled in the machine and driven by a gear 29 (see Fig. 1) from any suitable power source. These rolls 27 are provided with high points 30 between which and the blocks the sheets are nipped and prevented 85 from slipping on the cylinder after the pins have been withdrawn from the sheets. As the rolls rotate the high points move away 90 from the blocks and permit the sheet to be freely withdrawn by the folding off rolls. With this construction the sheet is firmly 95 held against the cylinder and at the same time the mechanism will adjust itself to automatically take care of products of varying number of plies.

In constructions embodying the invention in its best form a sheet cutting cylinder is employed co-operating with the rotary folding cylinder, and means are preferably provided to provide a device for assisting the pins or other sheet taking devices to advance the product past the cutting cylinder, as in certain cases there is a tendency for 100 the sheet to drag as it gets between the folding cylinder and the cutting cylinder which results in a tearing of the sheet at 105 the point where it is engaged by the pins.

While these devices may vary somewhat in construction, they may include spring seated blocks 31, 32 similar to the blocks already described, these blocks being yieldingly mounted to accommodate products of varying number of plies, these blocks being arranged just in front of the pins or other sheet taking devices and assisting the pins or other sheet taking devices to forward the web past the cutting points.

The tucking blade tucks the sheet, as before stated, in the bite of a pair of folding 110 rolls 34, 35 from which the folded product may be delivered by the ordinary fly delivery 36 by which it may be piled on any suitable transferring device as tapes 37 for 115 removing from the machine.

The operation of the mechanism will be clear from the description and drawings, but may be briefly stated as follows—

Referring first to Fig. 4 the end of the 120 ply has been taken by the pins 14 and been 125

advanced almost to the point where the pins are withdrawn from the sheet the tucking blade not having yet come into action, and the sheet not having yet been severed from the web. In Fig. 5 the parts are shown a little further advanced. The sheet has now been cut from the web and the folding blade is just starting to fold off the sheet and the pins have been withdrawn. At this time the high part 30 of the abutment roll is in contact with the blocks and the sheet is held firmly between the blocks and abutment roll and back slip of the sheet prevented. In Fig. 6 the parts are still further advanced, and the sheet has now been tucked into the nip of the folding rolls 34, 35 and the high part 30 of the abutment roll is just running off the blocks, and Fig. 3 shows a continuation of the movement where the sheet has been nipped in the bite of the rolls and is free to be withdrawn thereby.

While the invention has been shown and described in its preferred form, it will be understood that certain changes and variations may be made in the specific structure by which the invention is carried into effect, and the invention is consequently not to be limited to the precise arrangement of the parts shown and described.

30 What is claimed is:

1. The combination of a rotary carrier, sheet taking devices thereon, a folding mechanism, acting to fold a sheet off the carrier, yielding friction devices on the carrier arranged behind the sheet taking devices, a co-operating abutment between which and said devices a sheet or sheets pass, said devices and abutment operating to prevent the sheet slipping on the cylinder 40 after it has been released by the sheet taking

devices and before it has been folded off by the folding mechanism.

2. The combination of a rotary carrier, sheet taking pins thereon, a folding mechanism acting to fold a sheet off the carrier, 45 spring seated friction blocks on the carrier arranged behind the pins, and a rotary abutment co-operating with the blocks to hold a sheet or sheets therebetween after they have been released by the pins and before 50 they are folded off by the folding mechanism.

3. The combination of a rotary carrier, sheet taking devices thereon, a folding mechanism acting to fold a sheet off the 55 carrier, yielding friction devices on the carrier arranged behind the sheet taking devices, a co-operating abutment between which and said devices a sheet or sheets pass, a cutting cylinder co-operating with the 60 carrier to sever a sheet, and yielding friction devices arranged on the carrier in front of the sheet taking devices to assist them in forwarding a sheet past the cutting point.

4. The combination of a rotary carrier, 65 sheet taking devices thereon, a folding mechanism acting to fold a sheet off the carrier, spring seated friction blocks on the carrier arranged behind the pins, a rotary abutment co-operating with the blocks to 70 hold a sheet therebetween after they have been released by the pins, a cutting cylinder co-operating with the carrier to sever a sheet, and spring seated blocks arranged on the carrier in front of the pins to assist 75 them in forwarding a sheet past the cutting point.

In testimony whereof, I have hereunto set my hand.

JOHN J. HALLIWELL.
